ELECTRICAL MEASUREMENT INSTRUMENT CASE

Norman E. Morrison and Perry H. Rosen, Portland,
Oreg., assignors to Electro Scientific Industries, Inc.,
Portland, Oreg., a corporation of Oregon

Filed Mar. 22, 1965, Ser. No. 84,374

Term of patent 14 years

(Cl. D26—1)

Fig. 1.

Fig. 2.

Fig. 3.

FIG. 4.

FIG. 5.

FIG. 6.

FIG. 1 is a top plan view of an electrical measurement instrument case, showing our new design, in closed condition;

FIG. 2 is a front elevational view thereof;

FIG. 3 is a left-side elevational view thereof;

FIG. 4 is a view similar to FIG. 1 but showing the case in open condition;

FIG. 5 is a left-side elevational view thereof; and

FIG. 6 is a front elevational view thereof.

We claim:

The ornamental design for an electrical measurement instrument case, as shown.
